[57] CLAIM

The ornamental design for snow shovel, as shown and described.

DESCRIPTION

FIG. 1 is a front perspective view of snow shovel showing my design;

FIG. 2 is a top plan view thereof;

FIG. 3 is a front view thereof;

FIG. 4 is a rear view thereof;

FIG. 5 is a bottom view thereof;

FIG. 6 is a left side view thereof;

FIG. 7 is a right side view thereof;

FIG. 8 is a front perspective view of an alternate embodiment showing my design;

FIG. 9 is a top plan view thereof;

FIG. 10 is a front view thereof;

FIG. 11 is a rear view thereof;

FIG. 12 is a bottom view thereof;

FIG. 13 is a left side view thereof; and,

FIG. 14 is a right side view thereof.

The broken line showing of a portion of a handle in FIGS. 1 and 8 of the drawing is for illustrative purposes only and forms no part of the claimed design.
